UNITED STATES PATENT OFFICE.

CHARLES AUGUSTUS WOODHULL, OF NEW YORK, N. Y.

BANJO.

SPECIFICATION forming part of Letters Patent No. 450,442, dated April 14, 1891.

Application filed June 18, 1890. Serial No. 355,888. (No model.)

To all whom it may concern:

Be it known that I, CHARLES AUGUSTUS WOODHULL, a citizen of the United States, and a resident of New York city, in the 5 county of New York and State of New York, have invented certain new and useful Improvements in Banjos, of which the following is a specification.

My invention relates to an improvement 10 in banjos or other parchment-headed musical instruments, which I call a "resonance ring" or "hoop," and is intended to prevent the sound from being transmitted to the rim of the banjo or other instrument on which the 15 head is stretched, and thus produce a clear non-metallic sound, which is so noticeable in instruments of the class where parchment heads are used. It is well known that various devices have been devised to obviate 20 this—among others, metallic tubes with perforations. While instruments provided with such perforated tubes have to an extent overcome the metallic sound, yet the resonance-ring devised by me, and which I herein describe, I believe possesses the elements still 25 lacking in others to make it perfect, and an instrument provided with my mechanism produces the most agreeable tones, being melodious and penetrating without being either 30 metallic or harsh.

In the drawings, Figure 1 represents the ring or hoop E as applied to a banjo with a section of the head A cut away, exposing the hoop or ring E. Fig. 2 represents a cross-section showing the position of the ring or hoop E as applied to a banjo, in which the rim B, head A, stretching-hoop C, and hook D are shown.

Like letters represent like parts.

40 This resonance-ring is so constructed that it can be applied to any instrument now in use. Besides its application to banjos, I find that it gives great satisfaction when employed in tambourines, giving a clear ringing sound. 45 When applied to drums, the same effect is noticeable.

The resonance ring or hoop consists of a metallic hoop or ring in which the edges are turned inwardly toward each other in such a manner that a slot runs all around the inner 50 side or periphery of the ring or hoop, thus giving the air free circulation within the hollow, and by this means preventing the sound-waves from being transmitted to the body of the instrument. In practice I prefer to make the 55 hoop or ring a little larger than the head of the instrument, so that it will overlap the rim of the instrument to which it is applied. The parchment head is stretched over the ring in the usual manner or by other suitable 60 means.

I am aware that a patent was granted to Henry C. Dobson November 8, 1881, No. 249,321, for a metal ring having downwardly-projecting flanges upon which the parchment 65 head rests; and also the patent granted to James Morrison September 26, 1882, No. 264,893, in which he claims a metal ring supported on pins, &c.; but what I claim as new in the construction of parchment-headed mu- 70

75

cial instruments is a metallic tube having a continuous slot on the inner periphery or side thereof, which slot is on a line with the parchment head and which is placed between the rim or body of the instrument and the head.

Having described my invention, what I claim as new, and desired to secure by Letters Patent, is—

A parchment-headed instrument provided with a slotted metallic tube laid between the 80 parchment and the rim, the slot being on the inner periphery or side of the tube and running on a line with the head.

Signed at New York, in the county of New York and State of New York, this 24th day 85 of April, A. D. 1890.

CHARLES AUGUSTUS WOODHULL.
